UNITED STATES PATENT OFFICE.

EDGAR M. WILCOX, OF HAMMOND, INDIANA.

SWITCH MECHANISM.

Application filed August 25, 1926. Serial No. 131,333.

This invention relates to switch mechanism, and more particularly to switch throwing and locking means.

There is what is known as an interlocking switch for use both on main lines and in switch classification yards. The interlocking switch is satisfactory in so far as it holds a switch locked in open or closed position, but its main disadvantage is that it cannot be operated or thrown after a car comes within a predetermined distance of the switch, for example, about thirty feet. This is a decided disadvantage in so far as the classification yard is concerned for many times it is desirable to throw a switch and lock it in the thrown position when a car is within three or four feet of the switch.

Any switch which is not positively locked in one position or the other is dangerous in that the switch point may become slightly opened resulting in one truck or one car going down one track and the next truck or car going down the branch track, resulting in a wreck. This is a matter of not uncommon occurrence. As a matter of fact, most of the automatically operated switches in classification yards are not locked. As a result thereof, wrecks are caused resulting in a considerable expenditure of money.

It is highly desirable to have a quick acting automatically actuated switch locked in its closed position and prevented from easing back into an open position. Otherwise it will be apparent in the case of an air operated switch that when the switch is thrown to closed position under a pressure of sixty pounds, for example, and the air pressure gradually becomes reduced due to the usual leakage of air, the switch point will spring away from a closed position toward an open position resulting in wrecks.

Accordingly, one object of my invention is to provide switch operating mechanism, preferably of the automatically actuated type, which when the switch is thrown to a closed position it will be locked in that position regardless of how much leakage of air there may be.

Another object is to provide switch operating mechanism of the type above indicated in which it is necessary to provide a positive force to move the switch in an opposite direction or from its locked position.

A further object of my invention is to provide switch operating mechanism of the type above indicated which is completely

housed from the elements but which is readily accessible for repair or inspection.

Another object is to provide switch operating and locking mechanism adapted to meet the various requirements under service conditions.

These and other objects are accomplished by means of the arrangement disclosed on the accompanying sheet of drawings, in which—

Figure 1 is a fragmentary top plan view of track rails and switch points, and means for actuating and locking the switch points embodying my invention; 70

Figure 2 is a sectional view taken in the plane of line 2—2 of Figure 1; and

Figure 3 is a sectional view taken in the plane of line 3—3 of Figure 2. 75

The various novel features of the invention will be apparent from the following description and drawings, and will be particularly pointed out in the appended claims.

Referring to the figures of the drawings, it will be noted that my invention is illustrated in connection with track rails 10 and 11 and switch points 12 and 13 associated therewith. Heretofore switch points have been thrown by a single transversely extending bar which is connected to the switch point. In my arrangement, however, I provide two parallel arranged superimposed transversely extending and movable members or bars 14 and 15 which are arranged in a space 16 below the rails 10 and 11 and the switch points 12 and 13. Switch points 12 and 13 are connected to the upper transversely movable member 14 in any suitable manner such as by bolts 17 so that when the member 14 is moved to the right the switch points will be moved to the right, and when the said member is moved to the left said switch points will be moved to the left. Preferably the other transversely movable member 15 is located below the first transversely movable member 14 and is connected to a source of power such as a piston rod 18 connected to a piston (not shown) operable within a fluid pressure cylinder 19. Secured to the top transversely movable member 14 on the outer sides of each of the rails 10 and 11 is a plate 20 to which interconnected oppositely arranged toggle links 21 are pivoted at 22. The upper ends of the toggle links 21 are pivotally connected at 23 to a link in the form of a plate 24, the upper end of which is anchored at a point

just below the head of the associated rail. The lower ends of the links 21 pass downwardly between associated spaced pins 25 on the lower transversely movable member 15 by means of which motion may be transmitted from the lower transversely movable member to the upper one thereof and whereby the switch points in turn are actuated.

As shown in Figures 1 and 2 of the drawings, the switch point 12 has been moved to closed position and the switch point 13 into open position, and said switch points are positively locked in said positions. This is true because it will be noted that the pivotal point 23 of the toggle links falls below a straight line drawn between the pivotal point 22 of the toggle and a point 26 where the toggle link 24 is anchored below the head of the associated rail. The left hand toggle in Figure 2 is prevented from moving downwardly beyond the position shown because an overhanging lip portion 27 of the toggle plate 24 engages the plate 28 connecting the oppositely arranged toggle links 21. The switch points 12 and 13 have been moved into the position shown in Figure 2 by a left hand movement of the transversely movable member 15 and a corresponding but shorter movement of the upper transversely movable member 14. With the toggle links in the position shown, the switch points are positively locked in the positions indicated and it would make no difference how much air leakage there might be from the actuating cylinder 19. In order to break the toggle joint it is necessary to apply positive force in the opposite direction, or in other words, it is necessary to move the lower transversely movable bar 15 to the right as shown in Figure 2 for moving the pivotal point 23 upwardly for breaking the toggle joint. The continued movement of the transversely movable member 15 to the right, through the connections above described, will result in a corresponding movement of the upper transversely movable member 14 and of the switch points, the switch point 12 moving to an open position and the switch point 13 to a closed position in which positions said switch points will be positively locked by the toggle mechanism shown at the right hand side of Figure 2.

A housing is provided for the switch mechanism as shown in Figures 1 and 2, comprising a lower casing member made up to form a sealed enclosure designated generally as 29, the top wall 30 of which is positioned between the upper and lower transversely movable members and is provided with openings 31, through which pass the toggle links 21. The end wall 32 is provided with an opening 33 through which the lower transversely movable member 15 passes, it being understood that there may be a similar opening at the opposite end in

which case the member 15 may be extended and the two openings may be constructed to serve as supporting bearings for said member. Centrally of the tracks and fixed relative to the two rails respectively are two cover plates 34 perforated as at 35 in a manner to permit the bolts 17 to pass therethrough and to move relative thereto. A third cover plate 36 is fixed to the switch points to move therewith and is positioned in a manner to cover the mechanism underlying the central part of the track while permitting free movement of the parts. The end housings comprise a casing 37 having one end snugly engaging the rail and having its lower edge contacting in sealed relation the top of the lower casing 29 in a manner to complete the housing for the switch mechanism, this casing being provided at its top side with an opening closed by a sliding cover plate 38 which can be removed to expose the switch operating mechanism.

By means of the arrangement hereinabove described, the objects of the invention are accomplished.

I claim:

1. In switch mechanism, the combination of a switch point, a transversely movable member connected to said switch point, a second transversely movable member, and means connecting said transversely movable members whereby when the second one is actuated it moves the first one for actuating the switch point and positively locking it in a given position.

2. In switch mechanism, the combination of a switch point, a transversely movable member connected to said switch point, a second transversely movable member, and toggle mechanism connecting said transversely movable members whereby when the second one is actuated it moves the first one for actuating the switch point and positively locking it in a given position.

3. In switch mechanism, the combination of a switch point, two parallel arranged transversely movable members, one of which is connected to said switch point, and means connecting said transversely movable members whereby when the other of said movable switch members is actuated it moves the first one for actuating the switch point and positively locking it in a given position.

4. In switch mechanism, the combination of a switch point, two transversely arranged interconnected members operatively associated with said switch point whereby when one of said members is actuated, the other is actuated for actuating the switch point and said actuating movement causing a locking of the switch point in a given position.

5. In switch mechanism, the combination of a switch point, two transversely movable members operatively associated with said

- switch point, and toggle mechanism connecting said members whereby when one of said members is actuated the other is actuated for moving said switch point.
- 5 6. In switch mechanism, the combination of a switch point, two transversely movable members operatively associated with said switch point, and means connecting said members whereby when one of said members is actuated the other is actuated for moving said switch point.
- 10 7. In switch mechanism, the combination of a switch point, two transversely movable members operatively associated with said switch point, and toggle mechanism connecting said members whereby when one of said members is actuated the other is actuated for moving said switch point and for locking said switch point in a given position.
- 15 8. In switch mechanism, the combination of a switch point, two transversely movable members one of which is connected to said switch point, toggle links connecting said members, and another toggle member pivotally connected to said links and anchored at a point whereby when one of said transversely movable members is actuated the other will be actuated for moving the switch point into a given position and positively locking it in said position.
- 20 9. In switch mechanism, the combination of two switch points, a transversely movable member connected to each of said switch points, a second transversely movable member, and means connecting said transversely movable members whereby when one of said members is moved it moves one of said switch points into open position and the other into closed position.
- 25 10. In switch mechanism, the combination of two switch points, a transversely movable member connected to each of said switch points, a second transversely movable member, and means connecting said transversely movable members whereby when one of said members is moved it moves one of said switch points into open position and the other into closed position and positively locks said switch points in said positions.
- 30 11. In switch mechanism, the combination of two switch points, two track rails associated therewith, a transversely movable member connected to said switch points, a second transversely movable member, and means on opposite sides of said rails connecting said members whereby when one is actuated the other is actuated for moving one of said switch points into closed position and the other into open position and for positively locking said switch points in said positions.
- 35 12. In switch mechanism, the combination of a switch point, two relatively movable members one of which is connected to said switch point, and means connecting said members whereby when one is moved the other is moved for actuating said switch point and said actuating movement positioning said connecting means so as to positively lock said switch point in a given position.
- 40 13. In switch mechanism, the combination of two rails and two switch points, means positioned beneath and on the outside of said rails for operating said switch points and a housing underlying said rails and having portions extending upwardly on the outside of said rails for enclosing said means.
- 45 14. In switch mechanism, the combination of two rails and two switch points, operating means for said switch points positioned beneath said rails and a housing therefore comprising a casing having openings in its top through which pass mechanism connecting said operating means and said two switch points.
- 50 15. In switch mechanism, the combination of two rails and two switch points, operating means for said switch points positioned beneath and on the outside of said rails, and a housing for said means comprising a casing having openings in its top through which pass mechanism connecting said operating means and said two switch points for enclosing said means beneath said rails, and a separate casing positioned above said first named casing engaging said rails for enclosing said means positioned on the outside of said rails.
- 55 16. In switch mechanism, the combination of two rails and two switch points, operating means for said switch points positioned beneath and on the outside of said rails, and a housing for said means comprising a casing having openings in its top through which pass mechanism connecting said operating means and said two switch points for enclosing said means beneath said rails, and a separate casing positioned above said first named casing engaging said rails for enclosing said means positioned on the outside of said rails, said last named casing having a removable cover.

Signed at Chicago, Illinois, this 21st day of July, 1926. 115
